UNITED STATES PATENT OFFICE.

EINAR A. JOHNSEN, OF MOUNTAIN LAKES, NEW JERSEY.

CONDENSER.

Application filed January 11, 1924. Serial No. 685,526.

To all whom it may concern:

Be it known that I, EINAR A. JOHNSEN, a citizen of the United States, residing at Mountain Lakes, Morris County, and State of New Jersey, have invented an Improvement in Condensers, of which the following is a specification.

My present invention relates to a surface condenser and more particularly to that type of single pass condensers adapted for use in turbine practice, although, as will be understood, the invention is not necessarily limited to the single pass type of condenser or to being employed as a condenser for a steam turbine. Condensers of the type to which my invention relates are necessarily relatively large in order to provide for the necessary capacity of the apparatus and it is customary to provide support plates at intervals for maintaining the tubes in position in the shell to prevent the tubes from sagging and to guard the same against unnecessary vibrations. These support plates divide the interior of the condenser shell into a plurality of transverse compartments. Obviously, the number of support plates necessarily employed depends upon the length of the tubes and the size of the condenser.

In condensers of this type considerably more steam is condensed at the end at which the cold circulating water is admitted and there is comparatively little condensing effect produced at the opposite end of the condenser where the circulating water leaves the apparatus. In this practice the steam enters the condenser at a relatively high velocity and in order to distribute the steam proportionately to the condensing capacity in all parts of the condenser it is necessary to place the exhaust steam inlet adjacent the circulating water inlet of the condenser and also to provide a plurality of adjustable baffle or directing plates to distribute the steam into the several compartments of the condenser so that each section thereof will operate efficiently. In so doing I have also found it necessary to arrange an outlet in each of the several compartments for the condensate and the non-condensable gases and to employ a suitable means for regulating each outlet in order to cause every tube in each compartment to do its share of the work whereby some of the steam as admitted to each compartment reaches the lowermost tubes before being condensed, and as will

be understood the construction and use of such a condenser apparatus results in a condensate of high temperature and permits of the use of a smaller condenser with less tube surface for any required service than those now ordinarily employed.

The condenser made in accordance with my invention will be hereinafter more particularly described in conjunction with the accompanying drawings, in which,—

Fig. 1 is a side elevation and partial section of my improved condenser apparatus, and

Fig. 2 is an end view and partial transverse section of the same on an enlarged scale.

Referring to the drawing the condenser shell is indicated at 10. This is made in the customary manner by being provided at the ends thereof with flanges 11 and 12. Adjacent the flange 11 there is a tube plate 13 and similarly adjacent the flange 12 there is a tube plate 14. These tube plates and the water boxes hereinafter described are secured together and to their respective condenser shell flanges by bolts or otherwise in the customary manner. Extending through the condenser shell and suitably connected at their ends in the tube plates 13 and 14 there is a plurality of tubes 15. At one end of the condenser there is a water box 16. This is provided with flanges 17 and 18, the former being connected to the adjacent tube plate and flange of the condenser shell and the latter being connected to the usual bonnet 19 to close the water box. As indicated the water box may be provided with a plurality of hand holes each normally closed by a cover indicated at 20. The water box 16 is also fitted with the usual inlet nozzle 21 for the admission of the circulating water. As illustrated this circulating nozzle is at the lower end of the box and in an offset position. However, as will be understood this inlet nozzle may be placed in any position.

At the opposite end the condenser is fitted with a water box 22. This is provided with flanges 23 and 24, the former being connected to the tube plate 13 and the adjacent end flange of the condenser shell as hereinbefore stated, and the latter is connected to a bonnet 25 to close the water box. This water box may also be provided with a plurality of hand holes each of which is normally

closed by a hand hole cover 26. The water box 22 is furthermore provided with the usual circulating water outlet nozzle as indicated at 27. This outlet nozzle as illustrated is at the top of the water box, but, as will be understood, may be placed in any position relative thereto.

Interiorly the condenser shell is divided into a plurality of compartments by partition walls 28. The condenser tubes 15 pass through and are supported by these partition walls which extend transversely across the condenser shell. The condenser shell is also provided preferably at the top thereof, 15 as shown in this instance, with a nozzle 29 adapted to be connected to the exhaust pipe from a turbine or other translating apparatus. At the upper ends of the partition walls 28 or connected to other parts of the 20 same adjacent the exhaust steam inlet nozzle I employ baffle plates indicated at 28', 29'. These baffle plates are of any suitable configuration and are preferably hinged to the extremities of the partition walls adjacent 25 the exhaust steam inlet and may be adjusted either exteriorly or otherwise to the required position for directing predetermined quantities of steam to the several compartments of the condenser. Any means, however, may 30 be employed for mounting and adjusting these baffle plates for thus directing the passage of the exhaust steam.

The number of partition walls and the resultant compartment into which the interior 35 of the condenser shell is divided may be varied as occasion requires, it being within the scope of the invention to employ any number of these partition walls and compartments. As illustrated, I have shown two 40 partition walls dividing the interior of the condenser into three compartments of substantially equal size. In the bottom of the shell of the condenser there is an outlet for the condensate and non-condensable vapors 45 from each compartment. As illustrated therefore, the bottom of the shell is provided with bosses 30, 31 and 32 centrally of which are the outlets 33, 34 and 35 respectively. Each of these condensate outlets is provided 50 with a valve for regulating the passage of the condensate and non-condensable vapors therethrough. These valves are similar in construction and are indicated at 36, 37 and 38, one of the same being shown in section. 55 Each of these valves includes a valve body 39 having a valve seat 40 adapted to receive a valve 41 operated by a valve stem 42. The valve stem 42 as indicated preferably passes 60 through a suitable stuffing box 43 and is journaled in a bearing provided for this purpose in a yoke 44, while at its outer end the valve stem is fitted with a hand wheel 46 for turning the same to adjust the position of the valve relatively to its seat. It will be 65 noted that the valve seat is preferably coni-

cal and the valve of like configuration so as to conform thereto and to enter the valve seat to any desired extent in order to control the passage of the condensate and the non-condensable vapors from the condenser 70 compartment with which the valve is associated.

The valves are connected by pipe sections 46, 47 and 48 forming a continuous discharge pipe leading to a stand pipe 49 or other connection which, as illustrated, communicates at one end 50 with a cooler for the gases and at the other end 51 to a condensate pump for disposing of the condensate.

I claim as my invention:

1. In a surface condenser a shell, tubes extending within the shell, partition walls extending upwardly from the bottom of the condenser to points adjacent the top thereof, and dividing the condenser shell into separate and distinct compartments, and means at the upper ends of the partition walls for directing exhaust steam into the several compartments within the condenser shell. 85

2. In a surface condenser, a shell, a plurality of condenser tubes within the same, partition walls dividing the interior of the condenser into a plurality of compartments, and means associated with and adjustable to position on the said partition walls for controlling the passage of exhaust steam into the several compartments in the condenser shell. 95

3. In a surface condenser a shell having an exhaust steam inlet, a plurality of tubes within the shell, partition walls extending from the bottom of the condenser upwardly to points adjacent the top thereof, and dividing the shell into a plurality of separate and distinct transverse compartments, the said shell having a condensed steam outlet for each of the said compartments, and means for separately regulating the discharge of the condensate and non-condensable vapors from the condensed steam outlet of each of the said compartments. 100

4. In a surface condenser, a shell, a plurality of tubes within the shell, partition walls dividing the shell interiorly into a plurality of transverse compartments, the said shell having an exhaust steam inlet and a condensed outlet in each of the said compartments, and adjustable devices associated with the said partition walls for directing and controlling the passage of the exhaust steam to the said compartments of the condenser shell. 115

5. In a surface condenser, a shell, a plurality of tubes lying within the said shell, means for passing a circulating medium through the said tubes, the said shell having an exhaust steam inlet adjacent the end at which the circulating medium is admitted to the condenser tubes, partition walls ex- 125 130

tending upwardly from the bottom of the condenser shell to points adjacent the top thereof, and dividing the shell transversely into a plurality of separate and distinct compartments, and adjustable means adjacent the upper ends of the said partition walls for directing the passage of the exhaust steam into the several compartments within the condenser shell.

10 6. In a surface condenser, a shell, a plurality of condenser tubes within the said shell, means for causing a circulating medium to flow through the said condenser tubes, the condenser shell having an exhaust steam inlet adjacent the end at which the circulating medium is introduced into the said tubes, a plurality of partition walls within the said condenser shell extending from the bottom thereof, upwardly to points adjacent the top thereof, the said partition walls dividing the interior of the condenser into a plurality of separate and distinct transverse compartments, the condenser shell also having a separate condensate and non-condensable vapor outlet from each of the said compartments, and means associated with the said condenser shell for controlling the passage of the condensate and non-condensable vapors through the said outlets

30 7. In a surface condenser, a shell, a plurality of condenser tubes within the shell, means for causing a circulating medium to flow through the said condenser tubes, the said condenser shell having an exhaust steam inlet adjacent the end at which the circulating medium is introduced into the said tubes, a plurality of partition walls dividing the interior of the condenser into a plurality of transverse compartments, a baffle plate adjustably connected to each partition wall to be adjusted for directing the exhaust steam into the several compartments of the condenser, the condenser shell having a condensed steam outlet for each of the said compartments, and means associated with the condenser shell for controlling the passage of the condensate and non-condensable vapors through the condensed steam outlet from each of the transverse compartments within the shell.

8. In a surface condenser, a shell, a plurality of condenser tubes within the said shell, means for causing a circulating medium to flow through the said condenser tubes, the condenser shell having an exhaust steam inlet adjacent the end at which the circulating medium is introduced into the said tubes, a plurality of partition walls within the said condenser shell extending from the bottom thereof, upwardly to points adjacent the top thereof, the said partition walls dividing the interior of the condenser into a plurality of separate and distinct

transverse compartments, the condenser shell also having a separate condensate and non-condensable vapor outlet from each of the said compartments, valves each associated with one of the outlets for the condensate and the non-condensable vapors from the compartments within the condenser shell, and a common pipe line to which the said valves are connected.

9. In a surface condenser, a shell, a plurality of condenser tubes within the shell, means for causing a circulating medium to flow through the said condenser tubes, the said condenser shell having an exhaust steam inlet adjacent the end at which the circulating medium is introduced into the said tubes, a plurality of partition walls dividing the interior of the condenser into a plurality of transverse compartments, a baffle plate adjustably connected to each partition wall to be set in position for directing the exhaust steam into the several compartments of the condenser, the condenser shell having a condensed steam outlet for each of the said compartments, a valve associated with each condensed steam outlet for controlling the passage of the condensate and the non-condensable vapors from each compartment of the condenser, and a common pipe line to which the said valves are connected.

10. In a one pass surface condenser, a condenser shell, a water box at each end of the condenser shell, a plurality of tubes lying within the condenser shell and through which a circulating medium passes from one water box to the other, the said condenser shell having an exhaust steam inlet adjacent the water box at which the circulating medium enters the said tubes, partition walls extending from the bottom of the condenser shell upwardly to points adjacent the top thereof, and dividing the interior of the condenser shell into a plurality of separate and distinct compartments, means at the upper ends of the said partition walls for directing the passage of exhaust steam into the said compartments, the said condenser shell having a condensate and non-condensable vapor outlet for each compartment, and means associated with each outlet for the condensate and non-condensable vapors for controlling the discharge and passage of the same from the several compartments of the condenser.

11. In a one pass surface condenser, a shell, a water box at each end of the shell, a plurality of tubes lying within the condenser shell and through which a circulating medium passes from one water box to the other, the said shell having an exhaust steam inlet adjacent the water box at which the circulating medium enters, partition walls dividing the interior of the shell into a plurality of transverse compartments, a

- baffle plate hinged to each partition wall and adjustable to position to direct the flow of exhaust steam into the several compartments, the said shell having a condensed steam outlet for each of the said compartments, and means associated with the shell for controlling the passage of condensate and non-condensable vapors through each of the said condensed steam outlets.
- 19 12. In a one pass surface condenser, a shell, a water box at each end of the shell, a plurality of tubes lying within the condenser shell and through which a circulating medium passes from one water box to 15 the other, the said shell having an exhaust steam inlet adjacent the water box at which the circulating medium enters, partition walls dividing the interior of the shell into a plurality of transverse compartments, a 20 baffle plate hinged to each partition wall and adjustable to position to direct the flow of exhaust steam into the several compartments, the said shell having a condensed steam outlet for each of the said compartments, and valves each associated with the condenser shell and with one of the said 25 condensed steam outlets for controlling the passage of the condensate and non-condensable vapors through the condensed steam outlet 30 with which it is associated.
13. In a one pass surface condenser, a shell, a water box at each end of the shell, a plurality of tubes lying within the condenser shell and through which a circulating medium passes from one water box to 35 the other, the said shell having an exhaust steam inlet adjacent the water box at which the circulating medium enters, partition walls dividing the interior of the shell into a plurality of transverse compartments, a 40 baffle plate hinged to each partition wall and adjustable to position to direct the flow of exhaust steam into the several compartments, the said shell having a condensed steam outlet for each of the said compartments, valves each associated with the condenser shell and with one of the said 45 condensed steam outlets for controlling the passage of the condensate and non-condensable vapors through the condensed steam outlet 50 with which it is associated, and a pipe line common to all the said valves.

Signed by me this 28th day of December, 1923.

EINAR A. JOHNSEN.
